United States Patent Office.

JASPER SNELL AND JOHN M. CROSLAND, OF POTTSVILLE, PENNSYLVANIA.

Letters Patent No. 96,628, dated November 9, 1869.

IMPROVED RAILWAY-RAIL SPLICE.

The Schedule referred to in these Letters Patent and making part of the same

To all whom it may concern:

Be it known that we, JASPER SNELL and JOHN M. CROSLAND, citizens of the United States, and residents of the borough of Pottsville, in the county of Schuylkill, and State of Pennsylvania, have jointly invented and perfected a new and improved Railway-Rail Clutch and mode of preventing the inequalities and uneven surface at the joints or junction of the rails upon railway-tracks, thereby, in effect, forming a continuous rail, by clutching the ends, joints, or junction of the rails, and dispensing generally with the cumbrous cast-iron chairs now in use; and in addition thereto, the same may be applied to defects, breaks, or fractures of rails upon such roadways, by the use of a screw-punch, without the necessity of loosening chairs or taking up the rails; and we hereby declare that the following is a full and exact description thereof, which will enable others skilled in the art to make and use the same, reference being had to the accompanying drawings, which represent cross-sections of our improved combination for connecting the ends of rails upon railways.

The nature of our invention consists in a combination of three wrought-iron plates, one bottom and two side plates, which we call "a railway-clutch," the same being formed, first, by a bottom plate, A, with

side angles at both edges, of the width of the base of the rail, to which it is applied, to be placed under the point of junction of the rails, and between the cross-ties; second, a pair of side plates, B B, having a return-flange, that clutches the angles of the bottom plate, and being bolted through the rail in the usual manner of what are termed "fish-plates," compresses the ends of the rails downward on the bottom plate, while the latter holds them upward in equal force; and the combination thus formed, is intended to restore the full strength of a sound rail to the point of severance.

The length and strength of the clutch, and the number of bolts, two or four, may be left to the judgment of the parties using it.

What we claim as our invention, and desire to secure by Letters Patent of the United States, is—

The railway-rail clutch or splice, formed by the angular channel-bar plate A and the side plates B B, constructed and applied as set forth:

JASPER SNELL.
JOHN M. CROSLAND.
